LADING STRAP ANCHOR SHELF BRACKET

Franklin P. Adler, Michigan City, Ind., assignor to Pullman-Standard Car Manufacturing Company, Chicago, Ill., a corporation of Delaware

Application December 21, 1953, Serial No. 399,407

3 Claims. (Cl. 105—369)

This invention relates to mobile freight compartments and is primarily concerned with a movable bracket for supporting lading shelves.

The principal object of this invention is to provide an easily adjustable shelf bracket to be used with a lading strap anchor arrangement as a support for lading shelves.

Another object is to provide a rugged two-piece shelf bracket to be used with a lading strap anchor arrangement as a support for lading shelves.

And still another object of this invention is to provide a simple and inexpensive shelf bracket to be used with a lading strap anchor arrangement as a support for lading shelves and which may be quickly adjusted by hand.

A further object of this invention is to provide a shelf bracket to be used with a lading strap anchor arrangement as a support for lading shelves and which offers practically no obstruction to lading adjacent thereto and below the lading shelf held by the bracket.

And yet a further object is to provide a shelf bracket to be used with a lading strap anchor arrangement as a support for lading shelves and which provides simple means for attaching the shelving material securely to the bracket.

Another object of this invention is to provide a shelf bracket to be used with a lading strap anchor arrangement as a support for lading shelves which may be readily located therewith so as to handle various sized lading.

The foregoing and other objects of this invention are attained by the construction and arrangement illustrated in the accompanying drawings in which

Fig. 1 is a fragmentary vertical view of the inner face of a freight compartment showing the invention in use with lading strap anchor arrangements and lading shelves;

Fig. 2 is a fragmentary sectional view of the compartment taken along line 2—2 of Fig. 1;

Fig. 3 is an enlarged fragmentary view, partly in section, taken from Fig. 1;

Fig. 4 is an enlarged fragmentary view, partly in section, taken along the line 4—4 of Fig. 3;

Fig. 5 is a fragmentary view of the invention, partly in section, taken along the line 5—5 of Fig. 4; and

Fig. 6 is a fragmentary perspective view of the invention distinctly showing the two-piece arrangement of the shelf bracket and being partially installed in the lading strap anchor arrangement.

This invention proposes a shelf bracket for supporting lading shelves to be used in conjunction with a lading strap band anchor arrangement disclosed in my co-pending applications, Serial Number 252,033, filed October 19, 1951, and Serial Number 323,058, filed November 28, 1952. As these co-pending applications describe the lading strap anchor arrangement in detail, my description of said arrangement shall be concise.

For decades the freight industry has been faced with the problem of properly handling lading consisting of various sized packages having varying degrees of weight. There exist innumerable situations where certain types of packages may not be placed one upon another for the

2

entire available height of the freight compartment, therefore the necessity is present to provide supporting means for lading capable of vertical adjustment within the compartment and being attained with simplicity of design and handling. To an improved solution of this problem the present invention is directed.

The lading strap anchor arrangement shall be described with respect to one unit, however it is evident from Figs. 1 and 2 that a plurality of these units are to be used in a freight compartment.

Referring now to the drawings, a freight compartment generally designated 10, has a side wall 11, a floor 12, a roof 13, outer wall paneling 14, corner posts 15, door 16, door posts 17, intermediate posts 18, and lading shelves 19.

Lading anchor arrangements comprise an elongated guide plate 20, being channel shaped with outer turned ends, a lading anchor 21 which is an elongated strip of metal having opposite side portions 22 turned inward at successive vertical equi-distant points, leaving the intermediate side portions 23 as openings. The guide plate and the anchor are secured to an intermediate post 18 by usual means, such as nut and bolt units 24. Furring strip 25 is placed adjacent the intermediate post 18, being spaced from the wall paneling 14 by a flange 26 of the post and being flush with the inner surface of the intermediate post. Furring strip 27 is placed on the other side of the post 18 and is also flush with the inner surface of the post. A spacing clip 28 is secured to the intermediate post 18 and spaces the furring strip 27 therefrom. The clip 28 has an extension 29 which extends parallel to and between the strip 27 and the paneling 14 and serves to space the strip 27 from the wall paneling 14 and also provides lateral support for the strip 27. A nut and bolt unit 30 may be inserted through the furring strip 25, the intermediate post 18 and the furring strip 27 to clamp the units together. Inside wall lining 31 is then secured to the furring strips 25 and 27 and adjacent to the guide plate 20 (Fig. 6).

A shelf bracket (Fig. 6) generally designated 32, is comprised of two pieces, a support member 33 and a carrier member 34. The support member is substantially flat, having an offset lower portion 35 and a curved flange 36 substantially at right angles to the majority of the member 33. The carrier member 34 is hingedly connected, by an ordinary type hinge 37, to the support member and extends at right angles thereto. The carrier member is channel shaped, having a flat base 38 and upturned edges 39. Stops 40 and 41 are secured, as by welding, to the bottom of the base 38, and nail and bolt openings 42 and 43 are provided in the base for reasons hereinafter discussed.

When placed in operation, the carrier member 34 is rotated outwardly away from the support member 33. The flange 36 of the support member 33 is then inserted in an anchor opening 23 until the member 33 is substantially at right angles to the lining 31 and the lower portion 35 is resting against the guide plate 20. The carrier member 34 is then rotated on its hinged connection 37 to rest on top of the support member 33 in a horizontal position. For vertical support, the contact of the carrier 34 and the support 33 is substantially midway between the ends of the carrier 34. Lateral support to prevent the carrier from moving longitudinally is provided by an offset center stop 40, which rests adjacent one side of the support member 33, and by a corner stop 41 which is on the other side of the support, resting in between one side of the anchor 21 and the adjacent side of the guide plate 20.

After installation of the shelf bracket 32, longitudinal shelving material 44 is secured to the bracket by means of bolt units 45 and nails 46. Then when opposing

brackets 32 are placed in exact vertical positions, transverse shelving material 47 may be attached to the longitudinal material 44, as by nails 46. Shelf supports 44a are secured to the wall lining at the end of the material 44 for support. These may be readily attached or removed by using screws.

By the proposed arrangement, it may be seen that a variety of lading shelf positions may be attained by the use of a readily adjustable, rugged shelf bracket which may be quickly and easily placed into use or removed therefrom, and which may be used in conjunction with a dual purpose lading strap anchor arrangement. It may also be noted that shelving material may be quickly applied to or removed from the shelf brackets with a minimum of handling, and that the only obstruction offered to the lading below the bracket is a comparatively short, substantially vertical strip of the bracket.

What is claimed is:

1. In combination with a freight-carrying compartment having side walls and a plurality of longitudinally spaced upright lading strap anchoring members rigidly secured to said walls each provided with a plurality of vertically spaced and vertically extending side-opening slots for anchoring lading straps, a lading shelf supporting bracket removably mounted in at least some of said slots comprising a support member and a carrier member, said support member comprising a vertically extending plate having a body portion terminating rearwardly in its lower zone in a vertical edge and in its upper zone in a flange extending substantially right angularly from the body portion directly above said edge and terminating at its top in a horizontal upper edge normal to said vertical rear edge, and said carrier member comprising a plate having a width substantially equal to the length of said upper edge of the support member, hinge means pivotally mounting said carrier member on the front of said upper edge of the body portion for swinging movement only about an axis transverse to the body portion and parallel to the length of the carrier member between an operative position wherein the carrier member rests on said upper edge of the body portion of the support member and an inoperative position elevated therefrom, and a stop element secured to and projecting rearwardly from the carrier member when the carrier member is in operative position on the support member, in horizontally spaced relation to the rear edge of the support member, whereby the support member may be mounted on the lading strap anchoring member by first inserting its flange in the slot

thereof with its vertical rear edge bearing against said anchoring member and then swinging the carrier member down from elevated to operative position wherein the rear edge of the carrier member is positioned adjacent the front surface of the anchoring member and the carrier member is horizontally disposed for supporting a shelf element with the stop element of the carrier member positioned adjacent one side surface of the anchoring member and cooperating with the flange of the support member positioned adjacent the other side of the anchoring member to fix the bracket against lateral movement.

2. The combination claimed in claim 1, in which the lower zone of the body portion of the support member is offset in the direction in which the flange extends, whereby the vertical rear edge of the body portion bears against the lading strap anchoring member in a vertical plane offset from the plane of the vertex of the angle formed by the flange and the body portion of the support member.

20 3. The combination claimed in claim 1, including a center stop element secured to and projecting below the bottom surface of the carrier member adjacent a side surface of the support member when the carrier member is in operative position to assist in bracing the carrier member against horizontal movement transversely of the support member in one direction.
